UNITED STATES PATENT OFFICE.

THOMAS G. JONES, OF EAST ORANGE, NEW JERSEY.

DESIGN FOR A BOWL.

54,850.

Specification for Design.

Patented Apr. 13, 1920.

Application filed November 18, 1919. Serial No. 338,979. Term of patent 14 years.

To all whom it may concern:

Be it known that I, THOMAS G. JONES, a citizen of the United States, residing at 81 Beach street, in the city of East Orange, county of Essex, and State of New Jersey, have invented a new, original, and ornamental Design for Bowls, of which the following is a specification, reference being made to the accompanying drawing, forming part thereof.

The figure is a side view of a bowl, showing my new design.

The dominant feature of my invention comprises the fluted portions A—A—A, etc., spaced at equal distances apart and having

located between them the combination of chair-bottom design elements B—B—B, etc., and each of which is depressed opposite the miter cut portions C—C—C, etc., the miter-cut portions being located opposite the chair-bottom design portions as illustrated.

Having thus described my invention, I claim:

The ornamental design for a bowl as shown and described.

In testimony whereof, I have hereunto set my hand and seal this 29th day of September, 1919.

THOMAS G. JONES. [L. s.]
